UNITED STATES PATENT OFFICE.

AUGUST WUENSCH, OF NEW YORK, N. Y.

BOX.

SPECIFICATION forming part of Letters Patent No. 361,662, dated April 19, 1887.

Application filed February 23, 1887. Serial No. 228,533. (No model.)

To all whom it may concern:

Be it known that I, AUGUST WUENSCH, of the city, county, and State of New York, have invented certain new and useful Improvements 5 in Boxes, of which the following is a specification.

The box to which my invention is directed is one intended for cravats—such cravats as are ready made up in the form of ties or scarfs. 10 It has been customary heretofore in packing these cravats to place piles of them in the box in a row, each pile of cravats of the row being separated from its neighbor by a covered coffin-like structure, as high as the box is deep, 15 and intended to hold the piles of cravats in place and separate from one another. These coffin-like structures are made of pasteboard, covered by some ornamental paper. They are somewhat difficult and expensive to make and 20 fit into place, and they obscure very much the contents of the box. As a matter of fact they cost nearly, if not quite, as much as all the rest of the box put together. It is my object to do away with these objectionable structures, and to 25 provide skeleton dividing-walls, which, while holding the cravats quite as securely in place, shall offer a minimum obstruction to viewing the contents of the box, and shall also reduce materially the cost of the box itself.

30 The nature of my invention can best be explained and understood by reference to the accompanying drawings, in which—

Figure 1 is a perspective view of a box embodying my invention in its preferred form. 35 Fig. 2 is a vertical section of the same on line xx , Fig. 3. Fig. 3 is a plan of that part of the box containing the dividing-walls. Figs. 4 and 5 are perspective views, in different stages of advancement, of one of the structures of 40 which the dividing-walls are made up. Fig. 6 is a perspective view of a modification. Fig. 7 is a vertical cross-section through one of the partitions of the box shown in Fig. 6.

The box shown in Fig. 1 is intended to hold 45 three piles of cravats in a row. The two end piles are separated from the center pile each by dividing walls or partitions of approximately the outline of a T. Of the head of the T the right-hand limb, 1, is longer than the left-hand limb, 2, this being to make the space inclosed 50 between each two of these skeleton dividing-

walls of a shape to conform to that of the bow of the cravat which is received and held between them, as indicated plainly in Fig. 1. The wall next to the two sides of the box is 55 of the shape of that half of the T appropriate to the side on which it is placed.

The space or opening between the heads of adjoining T's is just wide enough for the cravat at the junction of the bow and ends of the 60 scarf, and the ends project beyond this opening into the body of the box, as seen. The cravats are thus held firmly by their heads or bows, which fit snugly and are held securely 65 in the spaces bounded by the T-shaped dividing walls or partitions. These walls or partitions are conveniently made, as follows:

If there are to be three cravats in a row, then I take a box, such as is shown at A, in Fig. 4, of a length equal to one-third the width of the 70 box, of a width sufficient to accommodate the length of the bow portion of the scarf, and of a depth equal to that of the box. The box A is conveniently and cheaply made of a bottom piece and a strip sufficient in length for the four 75 sides, which is creased or partly slit at the proper points of bend, and is then bent around and secured at its lower edge to the bottom by a strip, a , of paper, which is pasted over the joint, as is customary. I then form the two longer 80 sides of this box, and cut out the pieces included between the dotted lines $b b$ and $c c$, Fig. 4, thus bringing the box to the condition shown in Fig. 5, with a space within it to receive the bow of the cravat, a comparatively 85 contracted opening, d , on one side for the passage of the ends of the cravat and a comparatively larger opening, e , on the other side for the broad top of the cravat above the bow and for the neckband x , Fig. 1, which usually 90 protrudes from this broad top in loop form.

It is preferred to preliminarily crease the sides on the lines $b b$ $c c$, so that the workman may have no difficulty in determining the lines of cut.

95 After preparing three such boxes, as shown in Fig. 1, they are put into the larger box, B, Fig. 1, and are then placed end to end, in which position they extend in line across from side to side of the box B, as shown plainly in Figs. 100 2 and 3. They are secured in this position to one another and to the box by paste, glue, or

other means usually employed for the purpose, and they are covered with paper, as indicated at *f*, so as to present the appearance of a homogeneous structure.

5 In the modification shown in Figs. 6 and 7 there is a bottom strip, *g*, which extends from side to side of the box *B*, and wooden partitions *h*, which constitute the shanks of the **T**'s, the heads *i* and feet *j* of the **T**'s being secured to these parts *h*, and the whole covered, as in the other instances, with paper.

Having described my improvement and the best way now known to me of carrying the same into effect, what I claim herein as new and of my own invention is—

1. The herein-described box for cravats, pro-

vided with **T**-partitions, arranged as shown and specified, to receive and hold between them the bows of the cravats, and to provide the openings *d e* for the ends and neckbands, 20 respectively, of the cravat.

2. The box *B*, provided with partitions formed by boxes *A*, having openings *d e* in their sides, and placed and secured in the box *B* end to end, as hereinbefore shown and de- 25 scribed.

In testimony whereof I have hereunto set my hand this 19th day of February, 1887.

AUGUST WUENSCH.
